(57) **CLAIM**

The ornamental design for a rosin box for stringed instruments, as show and described.

DESCRIPTION

FIG. 1 is a perspective view of a rosin box for stringed instruments showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
FIG. 7 is a bottom plan view thereof.

The broken line portion of the figure drawings is included to show unclaimed subject matter only and forms no part of the claimed design.
